(57) **CLAIM**

The ornamental design for a stylus, as shown and described.

DESCRIPTION

FIG. 1: Is a perspective view of the stylus shown in use;

FIG. 2: Is a top view of the stylus;

FIG. 3: Is a bottom view of the stylus;

FIG. 4: Is a rear view of the stylus;

FIG. 5: Is a front view of the stylus; and,

FIG. 6: Is a right side view of the stylus, the left side being a mirror thereof.

The broken lines shown in the drawings illustrate portions of the claimed design.
